UNITED STATES PATENT OFFICE.

JANE E. GILLESPIE, OF ATLANTA, GEORGIA.

WATER-HEATER.

1,077,828.

Specification of Letters Patent. Patented Nov. 4, 1913.

Application filed November 9, 1912. Serial No. 730,520.

To all whom it may concern:

Be it known that I, JANE E. GILLESPIE, a citizen of the United States, residing at Atlanta, in the county of Fulton and State of Georgia, have invented new and useful Improvements in Water-Heaters, of which the following is a specification.

This invention relates to heaters, the object in view being to provide a novel, convenient, and effective heating apparatus for domestic purposes, the same being especially designed for the purpose of heating water for the bath, and also for heating flat irons, the heater as a whole being portable, so that it may be readily taken from room to room.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a vertical diametrical section through the complete heater, showing the burner and oil font in elevation. Fig. 2 is a horizontal section through the same taken in line with the flat iron pockets.

The heater in its general construction resembles the ordinary kerosene heater now in common use, in that it comprises the usual cylindrical base 1, supporting legs 2, and oil reservoir 3 equipped with the usual burner 4.

In carrying out the present invention, the upper portion of the heater comprises a substantially cylindrical drum 5 of novel form, in that at several intervals around the periphery of the drum 5, the latter is indented or offset inwardly to form a series of flat iron holding pockets 6, having steeply inclined floors or inner walls 7, against which the bottom of an ordinary flat iron, shown in 8, is adapted to rest, as clearly shown in Fig. 1. The plan or shape of this pocket is best illustrated in Fig. 1, wherein it will be observed that it comprises an inclined floor 7, formed integrally with the main wall of the drum 5, said pockets being pressed into the drum by means of suitable dies. In order to insure the retention of the flat irons in their respective pockets, in conjunction with each of said pockets a keeper or socket piece 10 is provided the same extending across the lower portion of the pocket, as best illustrated in Fig. 1, and in connection

with said socket piece, I employ a handle supporting arm 11 provided with a downwardly extending tongue 12 removably fitted in the keeper or socket piece 10, as that when not in use the said handle support may be detached, thus doing away with any projecting part on the exterior of the drum. It will be observed that the handle support is concavo-convex in vertical cross section, thereby adapting it to embrace and effectively to hold the handle 13 of the flat iron, as shown in Fig. 1.

In addition to the bottom wall or shelf 14, upon which the oil reservoir 3 rests, the base of the heater is provided with a supplemental upper wall or floor 15, upon which is mounted a series of coil supporting brackets or chairs 16. Removably supported upon the chairs 16 is a water heating coil 17, which is surrounded by an asbestos drum or casing 18 provided with clips 19, by means of which it is secured to some of the convolutions of the coil 17, as clearly shown in Fig. 1. Thus the asbestos drum 18 is connected directly with and also removable with the heating coil, which is adapted to be withdrawn through the top of the drum 5 and replaced as frequently as necessary.

By reference to Fig. 1, it will be observed that both ends of the coil 17 are located at the top of the heater, the inlet terminal 20 of the coil being shown as connected by means of a hose clamp 21 to the adjacent end of a flexible hose 22 which may lead to a suitable supply faucet 23, shown conveniently as the faucet of a wash-stand or basin. The other terminal portion 24 of the coil extends upward from the bottom of the coil and slightly divergent to the upward general direction of the coil, and thence outward through an opening 25 in the outer drum 5, where it is equipped with a faucet 26 adapted to project over the adjacent rim of a tub. In order to provide for the terminal portion 24 of the coil, the drum 5 is provided with a tapering offset or hollow extension 28, as shown in Figs. 1 and 2, the said offset being larger at the upper end, which enables the heating coil with its asbestos casing or drum to be introduced into and removed from the outer casing or drum 5 of the heater. The top or cap section 29 of the heater is preferably hinged to the drum 5, thus admitting of the ready introduction and removal of the heating coil.

The parts of the heater not hereinabove particularly described may be constructed and arranged in any preferred manner.

From the foregoing description, it will be understood that the heater may be used as an ordinary heater for domestic purposes, but that in addition to such use, it may be employed for quickly heating water for washing or bathing purposes, and also for heating flat irons. In this way, the value of the heating device, as a whole, is greatly increased, and will recommend itself highly to house-keepers.

What is claimed is:

15. 1. In a heater, a cylindrical base, an outside cylindrical sheet metal drum supported thereby, an inside drum, a water heating coil contained within the inside drum to which it is attached and removable through the top of the outside drum together with the inside drum, and a circular series of coil supporting brackets within the outside drum.
20. 2. In a water heater, the combination with

a drum-supporting base, and an oil font and burner contained therein, of a cylindrical drum extending upwardly from and supported upon said base, a removable inside drum having an outside diameter less than the inside diameter of the outside drum, brackets extending upwardly from and fastened to the base, and a water coil fastened to the interior of the inside drum and having its bottom convolution supported on said brackets, one end portion of said coil standing upright upon the exterior of the inside drum, and both ends of the coil extending laterally over the top of the outside drum, whereby the inside drum and attached coil are both removable through the top of the outside drum.

In testimony whereof I affix my signature in presence of two witnesses.

JANE E. GILLESPIE.
